UNITED STATES PATENT OFFICE.

CHARLES H. JOHNSON, OF CHICAGO HEIGHTS, ILLINOIS.

FLUID-PRESSURE-OPERATED TOOL.

No. 796,217.

Specification of Letters Patent.

Patented Aug. 1, 1905.

Application filed August 5, 1902. Renewed June 24, 1905. Serial No. 266,848.

To all whom it may concern:

Be it known that I, CHARLES H. JOHNSON, a citizen of the United States, residing at Chicago Heights, county of Cook, State of Illinois, have invented a certain new and useful Improvement in Fluid - Pressure - Operated Tools; and I declare the following to be a full, clear, and exact description of the invention, such as will enable others skilled in the art to which it pertains to make and use the same, reference being had to the accompanying drawings, which form a part of this specification.

My invention relates generally to fluid-pressure - operated tools, and more particularly to valve mechanism controlling the admission and exhaust of fluid-pressure to the cylinder.

In fluid-pressure tools it is desirable that the valve controlling the supply and exhaust of pressure to the ends of the cylinder should be operated to cut off the supply from the respective sides of the piston before it reaches the end of its stroke, and it is also desirable that the valve should be quickly shifted from one position to the other and when shifted positively held by a preponderance of pressure in each position until the piston reaches the predetermined point in its stroke, when the supply and exhaust of fluid-pressure to the respective ends of the cylinder should be reversed.

An object of my invention is to provide a fluid-pressure-operated tool in which the supply and exhaust of pressure to the respective ends of the cylinder are controlled by a piston-valve, the reciprocation of which to its controlling positions will be quickly and certainly accomplished, and which when shifted will be firmly held in each position until again shifted by the piston reaching the proper predetermined point in its throw.

A further object of my invention is to provide in a fluid-pressure-operated tool a valve mechanism for controlling the supply and exhaust of fluid-pressure to the opposite ends of the cylinder comprising a differential piston-valve which will be retained in position to admit fluid-pressure to one end of the cylinder by the pressure of fluid exhausting from the other end of the cylinder and which will be automatically moved to its other position when the pressure of the exhaust fluid is overbalanced by fluid-pressure constantly exerted upon annular radial surfaces of the valve.

A still further object of my invention is to provide a fluid-pressure-operated tool of the

character referred to which will be simple in construction, inexpensive in manufacture, and efficient in operation.

The embodiment of my invention herein disclosed, generally described, comprises a valve mechanism controlling the supply and exhaust of fluid-pressure to opposite ends of the cylinder to reciprocate the piston therein and consisting in a differential piston-valve the movement of which to one position is effected by exposing an end thereof to the fluid-pressure in the back end of the cylinder, the valve being retained in such position by the fluid-pressure passing from the back end of the cylinder to an exhaust - port, while the movement of the valve to and its retention in its other position are effected by pressure flowing directly from the supply-port exerted on differential annular surfaces.

My invention will be more fully described hereinafter, with reference to the accompanying drawings, in which the same is illustrated as embodied in a convenient and practical form, and in which—

Figure 1 is a horizontal central section through the cylinder with the parts which fit within the cylinder shown in plan; Fig. 2, a cross-sectional view, on an enlarged scale, showing the valve mechanism, taken on line 2 2, Fig. 1; and Fig. 3, a view similar to Fig. 2, showing the valve in section and in a position opposite to that shown in Fig. 2.

Similar reference characters are used to indicate similar parts in the several figures of the drawings.

Reference-letter A indicates the handle of the tool, which may be of any suitable construction, in the present instance the same being shown as provided with a tubular extension A', surrounding the back end of the cylinder C. The handle may be secured to the cylinder by any suitable means—such, for instance as an inwardly-extending circular flange A³, formed within the extension A' and adapted to be engaged between the end of the cylinder C and a flange formed on the cylinder-head C', as clearly shown in Fig. 1.

A⁴ indicates a lever for unseating a throttle-valve. The latter, however, is not shown, as the same forms no part of my present invention.

The cylinder C is provided with a bushing c, one end of which is engaged by the tubular projection C² of the cylinder-head C'. The part C² is preferably exteriorly screw-threaded to engage screw-threads formed

within the end of the cylinder C, and thereby retain the cylinder-head, as well as the handle A, in position on the cylinder.

The end C⁶ of the cylinder is interiorly screw-threaded and is engaged by a ferrule G. A snap or die H is removably supported within the ferrule G, in which it is yieldingly retained by means of a spring-ring g, seated within an annular groove formed in the interior surface of the ferrule. The shank of the die H is reduced, as shown at h, thereby forming shoulders to serve as stops to limit the movement of the die through engagement with the spring-ring g. A chamber C⁴ is formed in the end of the cylinder between the ferrule and the end of the bushing c, within which is located a button L, having a reduced portion L' of a diameter substantially the same as the interior diameter of the ferrule, within which it extends. An exhaust-port l' leads from the chamber C⁴ and is closed by the button L, as shown in Fig. 1, when the die is in engagement with an object. A groove l² is formed in the interior wall of the chamber C⁴ to permit fluid-pressure to pass around the head of the button. The tension of the spring C³, which is located between the bushing c and the cylinder C, tends to move the button L, so as to open the exhaust-port l'.

A cylindrical valve-casing A² is located transversely beneath the back end of the cylinder and is preferably formed integrally with the handle A. The valve-casing is provided with a series of annular grooves, with which communicate ports a', a², and a³, registering with ports c', c², and c³, formed in the cylinder C. An exhaust-port a⁴ communicates with an annular passage formed between the end of the cap A⁵ and the valve-casing. The end of the casing opposite to the cap A⁵ is provided with a circular opening a⁵ in constant communication with the atmosphere. An annular supply-passage a is formed near the center of the valve-casing and communicates with a source of fluid-pressure, such communication being controlled, as is customary, by a throttle-valve of any desired construction.

The port c' communicates with a passage leading to a point within the cylinder slightly farther away from the chamber C⁴ than the length of the piston K, as shown in Fig. 1. The port c² communicates with the back end of the cylinder. The port c³ is extended to form a passage, which communicates with the front end of the cylinder, as shown in Fig. 1.

A bushing E is located within the valve-casing A² and is retained in contact with a circular flange around the opening a⁵ by means of the screw-threaded cap A⁵. The bushing is provided with a series of ports e, e', c², c³, and e⁴, which register with the corresponding ports a, a', a², a³, and a⁴, formed in the valve-casing. A circular opening e⁵ is formed in

the end of the bushing opposite to the cap A⁵ and is preferably concentric with the opening a⁵.

A differential piston-valve D is located within the bushing and controls the ports therethrough. The end D' of the valve is hollow and is provided with ports d', connecting the exterior surface of the valve with the hollow interior. An annular flange D¹ is formed on the valve at a point intermediate of the hollow end D' and the opposite closed end D² of the valve. A restricted passage d⁴ is formed through the radial flange D¹. An annular flange is formed around the end D² of the valve and is of a diameter slightly less than the exterior diameter of the end D'. The end of the bushing E is reduced in bore to conform to the diameter of the flange around the end of the valve D².

The several parts of the valve mechanism may be readily assembled and the valve easily removed from the bushing owing to the screw-threaded engagement between the cap A⁵ and the corresponding end of the valve-casing.

The operation of my invention is as follows: When the valve is in the position indicated in Fig. 2, fluid-pressure flows from the supply-port a, through the ports e in the bushing, around the reduced portion of the valve between the shoulder D³ and the annular flange D⁴, through ports e², a², and c², to the back end of the cylinder. As the front end of the cylinder is in communication with the atmosphere through ports c³, a³, e³, e⁵, and a⁵, hence the piston is moved toward the front of the tool and delivers a blow upon the button L, which communicates the impact of the piston to the snap or die H. When the piston has nearly reached the limit of its forward stroke, the port c⁴ is uncovered and fluid-pressure flows through the passage communicating with such port to the port e', thence through the port a' in the valve-casing, the ports e' in the bushing, through the ports d, to the hollow interior of the end D' of the valve. The valve is consequently moved from the position shown in Fig. 2 to that shown in Fig. 3, inasmuch as the area of the end D' is greater than the areas exposed to pressure tending to retain the valve in the position shown in Fig. 2. When the valve is in the position indicated in Fig. 3, the back end of the cylinder is placed in communication with the atmosphere through the following ports and passages: e², a², e², d⁴, e⁴, and a⁴. Fluid-pressure is then admitted to the front end of the cylinder to move the piston toward the back or handle end of the tool through the following ports and passages: a, e, d⁴, e³, a³, and c³. The valve D is retained in the position shown in Fig. 3 owing to the pressure of the exhausting fluid exerted on the end D' thereof, the degree of such pressure and its duration being regulated by the size of the exhaust-port a⁴ with respect to the size of the ports e², a², and b². When

the fluid has exhausted from the back end of the cylinder and is no longer exerted on the exterior of the end D' of the valve, the latter is moved from the position shown in Fig. 3 to that shown in Fig. 2, owing to there being a greater area normally exposed to pressure tending to move the valve to the position shown in Fig. 2. This normal tendency of the valve is due to the fact that the annular shoulder D³ is the same in area as the opposite surface of the flange D⁴, and consequently balances the same, while the area of the other surface of the flange D⁴ is greater than the area of the flange around the end D² of the valve. It is therefore evident that the valve will be moved to and retained in the position shown in Fig. 2 whenever the exterior surface of the end D' of the valve is exposed to atmospheric pressure and that the valve will only be moved to and retained in the position shown in Fig. 3 when the area of the end D' is exposed to sufficient pressure to overcome the difference in area between the flange D⁴ and the flange around the end D² of the valve. When the snap or die is forced against an object, the spring C³ is compressed, owing to the engagement between the adjacent ends of the die H and the reduced portion L' of the button L, as shown in Fig. 1. The exhaust-port l' is consequently closed when the button L is in position to receive the impact of the piston and communicate the same to the die H. When, however, the snap or die is out of contact with an object, the spring C³ expands, thereby forcing the piston and die outwardly, so as to uncover the exhaust-port l' and permit the fluid under pressure to flow from the front end of the cylinder to the atmosphere, and thereby discontinue the reciprocation of the piston. The expansion of the spring C³ moves the head of the button into engagement with the inner end of the ferrule G, and consequently prevents the impact of the piston from ejecting the die from the tool when not in contact with an object. The port d⁴ is restricted so that the movement of the piston toward the back end of the tool will be sufficiently slow to permit the complete exhaust of the fluid through the restricted exhaust-port d⁴.

From the foregoing description it will be observed that I have invented a fluid-pressure-operated tool in which the supply and exhaust of fluid-pressure to the opposite ends of the cylinder are controlled by a differential piston-valve which is retained in position to admit fluid-pressure to one end of the cylinder by the pressure of the fluid exhausting from the other end thereof and is automatically moved to its other position upon the escape of the exhausting fluid by pressure flowing directly through the supply-port.

While I have described more or less precisely the details of construction, I do not wish to be understood as limiting myself thereto, as I contemplate changes in form, the pro-

portion of parts, and the substitution of equivalents as circumstances may suggest or render expedient without departing from the spirit of my invention.

Having now fully described my invention, what I claim as new, and desire to secure by Letters Patent, is—

1. In a fluid-pressure-operated tool, the combination with a cylinder, of a reciprocating piston therein, a valve-casing having an open end communicating with the atmosphere and having ports communicating with the opposite ends of the cylinder, a differential piston-valve located in said casing controlling the supply and exhaust of fluid-pressure, said cylinder and valve-casing having ports and passages whereby said valve is retained in position to admit fluid-pressure to one end of the cylinder by the pressure of the fluid exhausting from the other end of the cylinder.

2. In a fluid-pressure-operated tool, the combination with a cylinder, of a reciprocating piston therein, a valve-casing having ports communicating with the opposite ends of the cylinder, a differential piston-valve located in said casing controlling the supply and exhaust of fluid-pressure, said cylinder having a passage controlled by the piston to admit fluid-pressure from one end of the cylinder to the valve-casing to move the valve into position to exhaust fluid-pressure from the said end of the cylinder, the pressure of the exhausting fluid retaining the valve in said position, and radial annular surfaces on said valve constantly exposed to fluid-pressure to move the valve and retain it in its reverse position.

3. In a fluid-pressure-operated tool, the combination with a cylinder, of a reciprocating piston therein, a valve-casing having ports communicating with the ends of said cylinder, a piston-valve controlling the ports in said casing and having annular radial surfaces constantly exposed to pressure from the supply-port tending to move the valve into position to admit pressure to the back end of the cylinder, said cylinder having a port controlled by the piston and communicating with one end of the valve-casing to move the valve into position to admit fluid-pressure to the front end of the cylinder and to exhaust pressure through the valve-casing from the back end of the cylinder, the valve being retained in such position by the pressure of the exhausting fluid and being automatically reversed when the pressure from the supply-port upon the annular radial surfaces overbalances the pressure of the exhausting fluid.

4. In a fluid-pressure-operated tool, the combination with a cylinder, of a reciprocating piston therein, a valve-casing having ports communicating with the ends of said cylinder, a piston-valve controlling the ports in said casing and having radial surfaces constantly exposed to pressure from the supply-port tending to move the valve into position to

admit pressure to the back end of the cylinder, one of said radial surfaces having a restricted port through which pressure passes to the front end of the cylinder and two of said radial surfaces forming a passage for the fluid-pressure to the back end of the cylinder, said cylinder having a port controlled by the piston and communicating with one end of the valve-casing to move the valve into position to admit fluid-pressure to the front end of the cylinder and to exhaust pressure through the valve-casing from the back end of the cylinder, the valve being retained in such position by the pressure of the exhausting fluid and being automatically reversed when the pressure from the supply-port upon the radial surfaces overbalances the pressure of the exhausting fluid.

5. In a fluid-pressure-operated tool, the combination with a cylinder, of a reciprocating piston therein, a valve-casing having exhaust-ports at its opposite ends, a supply-port near the center thereof and ports communicating with the opposite ends of the cylinder, said valve-casing also having a port between one of the exhaust-ports and a port leading to the back end of the cylinder communicating with the interior of the cylinder at a point distant from its front end slightly greater than the length of the piston through which fluid-pressure flows from the cylinder to reverse the valve, a differential piston-valve within the valve-casing controlling said ports, said valve being moved in a reverse direction and retained therein by the pressure of fluid flowing directly to the valve-casing from the supply-port.

6. In a fluid-pressure-operated tool, the combination with a cylinder, of a reciprocating piston therein, a valve-casing having ports communicating with the opposite ends of the cylinder, a differential piston-valve controlling said ports and having annular radial surfaces constantly exposed to fluid-pressure flowing from the supply-port tending to move the valve to and retain it in position to admit fluid-pressure to the back end of the cylinder, the valve being moved into position to admit fluid-pressure to the front end of the cylinder by fluid-pressure admitted to the valve-casing from the back end of the cylinder and retained in such position by the pressure of the fluid exhausting from the back end of the cylinder.

7. In a fluid-pressure-operated tool, the combination with a cylinder, of a reciprocating piston therein, a valve-casing having ports communicating with the opposite ends of the cylinder, a differential piston-valve controlling

said ports and having a hollow end and annular radial surfaces constantly exposed to fluid-pressure flowing from the supply-port tending to move the valve into and retain it in position to admit fluid-pressure to the back end of the cylinder the valve being moved into position to admit fluid-pressure to the front end of the cylinder by fluid-pressure admitted to the valve-casing from the back end of the cylinder and retained in such position by the pressure of the exhausting fluid passing through the hollow end of the piston from the back end of the cylinder.

8. In a fluid-pressure-operated tool, the combination with a cylinder, of a reciprocating piston therein, a valve-casing having ports communicating with the opposite ends of the cylinder, a differential piston-valve having four annular radial surfaces between two of which fluid-pressure passes to one end of the cylinder, such valve also having a restricted passage leading to the space between the other two radial surfaces through which fluid-pressure flows to the other end of the cylinder.

9. In a fluid-pressure-operated tool, the combination with a cylinder, of a reciprocating piston therein, a valve-casing having ports communicating with the opposite ends of the cylinder, a differential piston-valve having ends of different diameters and an intermediate radial flange forming annular passages between the same and enlarged end for the passage of fluid-pressure to one end of the cylinder, said flange having a restricted passage through which fluid-pressure flows to the other end of the cylinder, said valve-casing having exhausting-ports adapted to be placed in communication with the ports leading to the ends of the cylinder by the ends of the valve.

10. In a fluid-pressure-operated tool, the combination with a cylinder, a reciprocating piston therein, a valve-casing having exhaust-ports at the opposite ends thereof, a supply-port at substantially the center thereof, and ports communicating with the opposite ends of the cylinder intermediate of the exhaust-ports and the supply-port, a differential piston-valve within said casing controlling said ports, said cylinder having controlling-ports communicating with the valve-casing through which fluid-pressure flows to reciprocate the valve.

In testimony whereof I sign this specification in the presence of two witnesses.

CHARLES H. JOHNSON.
